INVENTOR.

George W. Prentice

UNITED STATES PATENT OFFICE.

GEORGE W. PRENTICE, OF PROVIDENCE, RHODE ISLAND.

BUTTON-FASTENER.

SPECIFICATION forming part of Letters Patent No. 358,481, dated March 1, 1887.

Application filed December 9, 1886. Serial No. 221,088. (No model.)

To all whom it may concern:

Be it known that I, GEORGE W. PRENTICE, a citizen of the United States, residing at Providence, in the county of Providence and State of Rhode Island, have invented certain new and useful Improvements in Button-Fasteners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My present invention relates to a new and useful improvement in button-fasteners for attaching buttons to boots, shoes, and other articles; and it consists, primarily, of forming a two-pronged or staple fastener from a blank cut from sheet metal, said blank having a central button-holding portion of reduced dimensions in cross-section, and gradually tapered or enlarged from said reduced portion outward to the ends, said blank adapted to be bent into staple form, all as will be hereinafter more fully described.

Figure 1 represents a plan view of my improved button-fastener blank. Figs. 2 and 3 are perspective views of two forms of staple fasteners made from my improved blank.

In carrying out my improvement the blank A is cut from sheet metal, substantially in the form shown in Fig. 1, the central or reduced portion, a, being the narrowest part of the blank, the sides of said blank being gradually tapered or enlarged from said reduced portion a outward to the points c c, forming the enlarged portions b b, as fully shown in the drawings. The points c c are preferably rounded, and may be thinned and sharpened, to more readily penetrate material in attachment. The blank thus formed is adapted to be bent into a staple-fastener having a crown or arch of any desired form, the reduced portion a comprising the button-holding part of the staple, while the enlarged portions b b form the prongs thereof.

Fig. 2 represents a center-loop staple made from my improved form of blank, the center loop being formed from the reduced portion 50 a, while the side tables and prongs are formed from the enlarged portions b b, the rounded ends c c comprising the penetrating-points of the fastener.

Fig. 3 represents a common form of staple 55 provided with an elongated crown or arch for holding the button, made from the reduced portion a, the prongs being made, as previously described, from the enlarged portions b b, as shown in the drawings.

A fastener made from my improved form of blank possesses decided advantages over fasteners made from other forms of blanks now in use. The metal in sight above the surface of material, when attached thereto, being of a 65 minimum amount, presents a neat and attractive appearance, and the strength of the fastener is distributed where it is the most effective—namely, on the under surface of the fabric—the enlarged ends of the blank making 70 strong reliable holding-prongs, which are not easily disengaged from the fabric when secured thereto.

I claim as new and desire to secure by Letters Patent—

1. An improved button-fastener blank cut from sheet metal, it having a reduced central section, gradually enlarged from said section outwardly to the ends, substantially as specified.

2. As an improved article of manufacture, a button-fastener made from the blank herein described, comprising a reduced central button-holding portion provided with a prong on each side thereof, said prongs being gradually 85 enlarged outwardly from the central portion to the ends, substantially as herein set forth.

In testimony whereof I affix my signature in the presence of two witnesses.

GEORGE W. PRENTICE.
